UNITED STATES PATENT OFFICE.

BENJAMIN K. TRAYLOR, OF EL CAMPO, TEXAS.

STORE SHELF AND LADDER CONSTRUCTION.

Application filed June 19, 1923. Serial No. 646,380.

To all whom it may concern:

Be it known that I, BENJAMIN K. TRAYLOR, a citizen of the United States, residing at El Campo, in the county of Wharton and 5 State of Texas, have invented new and useful Improvements in Store Shelf and Ladder Constructions, of which the following is a specification.

This invention relates to ladders of the 10 shelf-service type, such as are particularly adaptable for use in stores or other establishments where goods or other articles are stored upon shelving at such height as to be 15 out of the reach of persons standing upon the floor.

It is customary, where frequent access must be had to said high shelving for the purpose of taking down articles or for replenishing the shelving, to provide a ladder 20 for serving said shelving, and many establishments are now equipped with devices of this nature which are permanently mounted to slide laterally in front of the shelving so that they may be moved to any desired position.

My invention concerns itself with the provision of an adjustable shelf for a ladder of this type so arranged that a person can place a large quantity of goods, for instance a case 30 of articles, upon the adjustable shelf at one time, then elevate said shelf to a convenient height to be reached from the ladder, and finally climb the ladder to transfer the article from the adjustable shelf to the store 35 shelving.

One of the objects of the present invention is to so construct an adjustable shelf that it can be elevated or lowered by a person while the latter stands upon, or climbs 40 the ladder.

Another object relates to a construction by means of which the adjustable shelf is latched in the desired position of elevation by the simple act of letting go of it, and is 45 released from latched condition by the same grasping movement of the one hand by which it is elevated or lowered.

Still another object of the invention is to provide the shelf with adjusting means for 50 setting it level to compensate for the inclination of the ladder, the said means being movable through a sufficient range to permit the shelf to be used either on the right or left hand side of the ladder.

55 A further object of the invention is to provide an adjustable shelf having the charac-

teristics above set forth, and adapted to be attached to any shelf-service or other ladder now in use.

With the above and other objects in view, 60 my invention consists in the improved store shelf and ladder construction illustrated in the accompanying drawings, described in the following specification, and particularly claimed, and in such variations and modifications thereof as will be obvious to those skilled in the art to which my invention relates.

In the drawings accompanying and forming a part of this specification, and wherein 70 the preferred embodiment of my invention is illustrated:

Figures 1 and 2 are respectively front and side elevations of a shelf-service ladder having my improved adjustable shelf thereto 75 attached.

Figures 3 and 4 are respectively front and side elevations of the sliding truck which forms the support for the adjustable shelf.

Figure 5 is a cross section taken along the 80 line 5—5 of Figure 3, showing details of construction.

Figure 6 is a similar view of a slightly modified form of my invention in which the sliding truck grasps a separable rack bar instead of the side of the ladder.

Figure 7 is a perspective view of a portion of the separable rack bar.

Figure 8 is a view of the elements, in separated relation, comprising the shelf parts, 90 the shelf itself being omitted.

Figures 9 and 10 illustrate respectively, front and side elevational views of a fixed shelf supported near the base of the ladder.

Referring now in detail to the several figures, the numeral 1 represents in general a ladder comprising side members 2 and 3 which are provided at their lower ends with rollers 5 on which the ladder may move without friction across the floor. At their 100 upper ends the side members 2 and 3 are furnished with grooved wheels 6 which engage a track-bar 7, the latter being secured in any appropriate manner, as shown at 8 in Figure 1 across the front of a stack of shelving 9. As is usual in ladders, the lower end of the ladder is positioned farther from the shelving than the upper end, so that the ladder is inclined obliquely toward the front of the stack of the shelving. At least one of the side members of the ladder is furnished 110 with detents 10 for engagement by a ratchet

presently to be described. These detents may be of any desired form or character, being here figuratively shown as depressions in the surface of one of said side members.

5 A truck 11 is slidably arranged with respect to that side member of the ladder which has the ratchet engaging depressions 10, said truck supporting the adjustable shelf 12.

The truck 11, in its preferred form, consists of a frame portion which may be made of sheet metal formed with longitudinal flanges 13 having inturned edges 14, constituting channels which are adapted to embrace the side members of the ladder or 15 another member which may be attached to said side member, as will presently appear when a slight modification of the invention is described. The frame of the sliding truck is formed with a plurality of spaced lugs 15 20 affording bearings for the spindles of anti-friction rollers 16. In the embodiment of the invention shown in the present drawings the lugs are formed from integral spaced portions struck up from the sheet metal 25 blank of the truck, leaving apertures 17 in said frame between said lugs through which the rollers 16 extend to bear against the surface of the side member of the ladder.

The fitting 18, which is best shown in Figure 8 comprises a downwardly extending portion adapted to be adjustably secured to the truck 11 and a flange 19 extending right angularly thereto to which one end of the shelf 12 is attached. To a portion of said shelf remote from said end, the fitting 20 is secured, said fitting being here shown in the form of a flat bar having apertures therethrough to receive the securing means. The truck 11 is provided with a projecting end 21, affording an attaching means for the fitting 18, said end and said fitting being alignedly apertured as at 22 and 23 for the reception of a rivet 24 or other suitable pivotal securing means. Said end and the fitting 18 are provided, respectively, with a plurality of apertures 26 and 25, one or more of the apertures 25 being adapted to be selectively brought into registry with one or more of the apertures 26 by tilting the fitting 18 relatively to the truck. When any of said apertures have been brought into registry the fitting 18 may be maintained in the angular position assumed, relative to the truck, by means of the bolt 27 or other suitable means. It is apparent that the truck will always have the same degree of inclination as the side member of the ladder with which it is associated, while the shelf 12 may be set to a horizontal position by 60 properly adjusting the fitting 18, regardless of whether the shelf is used on the right hand side or the left hand side of the ladder.

A brace 28, which may be of any desired form or construction, is rigidly attached at 65 one end to the lower end of the truck 11 by

any suitable means, such as screws or bolts passed through apertures 29 in the frame portion of the truck and engaging said brace. The upper end of said brace is seated in a notch 30 formed in the under 70 face of the bar 20. The base of said notch is inclined, as shown at 31, at an angle equal to the angle of inclination assumed by the shelf, relative to the ladder, when adjusted to a horizontal position. A screw or 75 other suitable securing means passes through an aperture 32 in the bar 20 and into an aperture 33 formed in the upper end of the brace 28. The notch 30 is sufficiently wider than the upper end of the brace 28 to permit the bar 20 to assume an inclined position with the base 31 of the notch firmly in contact with the upper end of said brace, when the securing means passing through the aperture 32 is tightened. When installing 80 the shelf the bar 20 should be turned in such direction that the inclination of said bar, determined by the engagement of the base of said notch with the brace 28, shall be in the same direction as the direction of 85 inclination of the fitting 18 relative to the truck 11. When changing the shelf to the opposite side of the ladder it is necessary to reverse the position of the bar 20 so as to have the base of the notch 31 oppositely inclined. The brace 28 forms a handle, by the 90 grasping of which the shelf 12 may be raised or lowered.

The side member of the ladder upon 100 which the truck 11 is mounted is furnished, as previously stated, with a series of ratchet detents 10. A ratchet 33' is pivotally mounted upon the brace 28 near its lower end by means of the pivotal connection 34, 105 which passes through lugs 35 of the ratchet, said lugs in the preferred construction of the device, engaging the opposite sides of the brace 28. The ratchet is in the form of a lever having at one end a handle 36 and at the opposite end a nose 37, which nose 37 projects a slight distance beyond the lower end of the brace 28 and in position to engage the ratchet detents 10. A spring 38 between the handle end of the ratchet and the brace 28 normally holds the nose 37 in frictional contact with the side of the ladder and in position to engage with said detents, said nose being released from latching relation with said detents by pressing the handle 36 toward the side member 3 against the resistance of the spring 38. The handle 36 is positioned so as to be readily grasped by the hand when in the act of lowering or raising the adjustable shelf.

In the operation of my improved adjustable shelf, let it be assumed that it is desired to transfer articles from a case to shelving at a height beyond the reach of a person standing upon the floor. The person handling the goods, instead of carrying a few 130

articles up the ladder in his arms, and transferring them to the shelving, with the imminent risk of dropping some of them enroute, and then making repeated trips until 5 the contents of the case are finally transferred to the shelving, he first, while standing upon the floor, places the case of goods upon the shelf which is in a conveniently low initial position, and grasping the brace 10 28 and the handle 36 of the ratchet with one hand, simultaneously releases the nose 37 of the ratchet 33' from whichever detent 10 it may be in engagement and elevates the shelf with the case of goods to as high a 15 position as he can conveniently reach. At this point he releases his grasp upon the brace 28 and handle 36 of the ratchet and the nose 37 will automatically engage one of said detents. He then climbs the ladder 20 high enough to enable him to reach the brace 28 from a more advantageous position, and he again grasps the brace 28 with one hand, at the same time holding on to the ladder with the other hand. In this 25 manner the shelf may be elevated until it is opposite the point at which it is desired to transfer the articles from said case to the shelving. The goods may then be stored 30 upon the shelving without the necessity that the one handling the goods shall descend the ladder. In the elevation of the shelf the wheels 16 prevent the upper portion of the truck 11 from binding against the side of the ladder under the slight tilting movement 35 of the shelf occasioned by the upward push of the operator against the brace 28.

In order to adapt my invention for ready installation upon ladders now in use, I have provided a detachable rack bar 39 which is 40 shown in Figures 6 and 7 and which is provided with a series of ratchet detents 40 having a function similar to the detents 10 formed in the side of the ladder shown in Figures 1 and 2. This detachable rack bar 45 may be secured to the side 41 of any ladder, being preferably of greater width than said side. In this form of the invention the flanges 13 of the truck 11, instead of directly embracing the side 41 of the ladder, 50 slidably engage the projecting edges of the rack bar 39 permitting the adjustable shelf to function relative to said bar in precisely the same manner that it does in the form of invention illustrated in Figures 1 to 5 55 inclusive. The rack bar 39 is adapted to be secured to either side of the ladder 41 so that the adjustable shelf may be applied, when using this attachment, to either the right or left hand side of the ladder in 60 the same manner as when slidably mounted directly upon the side of the ladder.

In Figures 9 and 10 I have shown a stationary shelf which may be used in conjunction with my adjustable shelf or independently thereof. It comprises, essen-

tially, a platform 44 attached in any suitable manner to brackets 45 which preferably consist of angularly bent metallic members surrounding a pair of adjacent steps of the ladder, and being held in position by passing through a transverse plate 46 which abuts the rear edges of the side members of the ladder and to which the brackets 45 are clampably held by means of the nuts 47. It is obvious that, by removing the nuts 47 70 the plate 46 may be removed and the shelf 44 turned down so as to release the brackets 45 from their position with respect to the adjacent steps of the ladder, after which said shelf may be entirely removed, if desired, or may be secured in fixed relation to any other two adjacent steps.

While I have above described what I have found to be a very practical embodiment of my invention, it is nevertheless to be 85 understood that the store shelf and ladder construction may also be embodied in numerous other alternative constructions, and I accordingly reserve the right of adopting all such legitimate changes as may be fairly 90 embodied within the spirit and scope of the invention as claimed.

Having described my invention what I claim as new and desire to secure by Letters Patent is:—

1. In combination with a normally inclined ladder, a shelf support slidably mounted on said ladder, a shelf pivotally carried by said support, means for adjustably retaining said shelf in a horizontal 100 position upon whichever side of the ladder said shelf is arranged, a handle to be grasped for elevating said shelf, a ratchet on said handle cooperating with means associated with said ladder for holding said 105 shelf in various positions of elevation, said ratchet being formed with a portion to be grasped when the handle is grasped for releasing said ratchet in the act of elevating said shelf.

2. In combination with a normally inclined ladder, and adjustable shelf slidably mounted thereon, a handle to be grasped for elevating said shelf and a ratchet on said handle cooperating with means associated with said ladder for holding said shelf in various positions of elevation, said ratchet being formed with a portion positioned to be grasped when the handle is 115 grasped for releasing said ratchet in the act of elevating said shelf.

3. In combination with a normally inclined ladder, a shelf support slidably mounted on said ladder, a shelf carried by said support, a brace secured to said shelf 125 and support and affording a handle, to be grasped for elevating said shelf, a ratchet pivotally mounted upon said brace and normally engaged with means associated with said ladder for retaining said shelf in vari- 130

ous positions of elevation, said ratchet having a portion thereof in position to be grasped when the handle is grasped in the act of elevating said shelf for simultaneously releasing said ratchet.

4. An attachment for normally inclined ladders, comprising a rack bar adapted to be secured to a side member of a ladder on either side of the ladder, a shelf support 10 adapted to be slidably mounted upon said rack bar, a shelf pivotally carried by said support, means for adjustably retaining said shelf in a horizontal position upon whichever side member of the ladder said

shelf may be mounted, a handle associated ¹⁵ with said shelf to be grasped for elevating said shelf, a ratchet associated with said handle and normally engaged with said rack bar for holding the shelf in various positions of elevation, said ratchet having a portion adapted to be grasped for releasing ²⁰ said ratchet from the rack bar when the handle is grasped to elevate or lower said shelf.

In testimony whereof I have hereunto set ²⁵ my hand.

BENJ. K. TRAYLOR.
